UNITED STATES PATENT OFFICE.

CHARLES E. KEATOR, OF BROOKLYN, NEW YORK.

MACHINE FOR FINISHING HAT-BODIES.

SPECIFICATION forming part of Letters Patent No. 411,662, dated September 24, 1889.

Application filed April 8, 1889. Serial No. 306,307. (No model.)

To all whom it may concern:

Be it known that I, CHARLES E. KEATOR, a citizen of the United States, and a resident of Brooklyn, Kings county, New York, have invented a Machine for Finishing Hat-Bodies, of which the following is a specification.

My invention consists of an improved machine for the finishing of hat-bodies as they come from the battery to be made ready for the shaping-machine. In the ordinary method of making hats this finishing operation upon the hat-bodies is carried out by hand, and is termed the "pinning-out" process. The hat-body in the pinning-out process is laid folded or flattened out upon a bench or table, and a rolling-pin is rolled over it by the operator to smooth the hat-body and to drive out the moisture and to some extent to finish the felting operation. In some instances this has been attempted by machine; but usually in such cases, as in the hand process, the hat-body has been operated on while flattened out or folded. This leaves croze marks or creases on the line of the folds, which give trouble in the subsequent operations, as set forth more fully in an application for a patent filed by me April 8, 1889, Serial No. 306,308, for a method of finishing hat-bodies. My present invention of a machine is designed for practically carrying out that method.

In the accompanying drawings, Figure 1 is a front view of the machine, showing the dies separated; and Fig. 2 is a vertical section on the line 1 2, Fig. 1, but showing the dies brought together.

The essential feature of this machine is the pair of dies E and F, of which one is a male and the other a female die of the conical shape and about the size of the ordinary hat-body as it comes from the battery in the hat-factory. These dies are provided with means for heating them, and for this purpose they are made hollow and have inlet and outlet pipes p p' for steam. In order to provide for the introduction and removal of the hat-body, the dies are made so as to be freely moved apart, and for convenience I prefer to make the male die E movable from and toward the female die. I make this male die the lower one, as it is more convenient to put the hat-body onto the male die than to introduce

it into the female die. This die E, I therefore mount upon a movable base E', which is guided vertically within the frame-work B of the machine, and preferably upon tie-rods D. 55 These tie-rods unite a base-plate D' with the cross-head b at the top of the machine.

The lower die E and its base are counterbalanced by weights W, hung to cords or chains w, which pass over pulleys v v' on the frame, and are connected to the movable base E', as shown in Fig. 1. To operate the moving die I provide a toggle-joint consisting of a pair of levers g g', pivoted to each other, one lever being hinged to the under side of 65 the base of the die, while the other is secured to a cross-shaft G, mounted in bearings on the base-plate D'. Stops s on the adjacent ends of the toggle-levers, while allowing the pivoting-point to pass beyond the center line, as 70 shown in Fig. 2, prevent it from going too far. To operate the toggle I may provide on the end of the cross-shaft G a long hand-lever G', under the control of the operator; or a treadle T may be employed with or without the hand-lever. If a treadle is used, it may have an arm t, with a connecting-rod t' reaching to the joint of the toggle-levers. 75

The die F may be fixed rigidly in the frame; but I prefer to provide it with means for imparting to it a short reciprocating movement when desired. For this purpose the die may be guided upon the tie-rods D and hung to links H, which are guided in the cross-head and suspended by a connecting-rod h from an 85 eccentric i on a cross-shaft I. This shaft is mounted in bearings upon the cross-head of the frame and provided with a belt-pulley or gear to rotate it. By imparting motion to this shaft a short reciprocating motion may 90 be imparted to the die F. When this die is at the bottom of its downward movement, its position will be such that if the lower die is then elevated the hat-body placed upon the lower die will be pressed between the two. If 95 the upper die is left stationary, the hat-body will thus be subjected to heat and pressure, and this may be continued as long as necessary, with or without separating the dies, as often as desired by depressing the lower die. 100 The effect will be to drive the moisture out of the hat-body and to smooth it uniformly

all over without leaving any troublesome croze marks or creases in the hat-body, and so to greatly simplify and facilitate the subsequent operations.

5. If it be found desirable to complete the felting of the hat, the described reciprocating motion may be imparted to the upper die with the result of giving a pounding or rubbing action to the hat-body while held on the lower die in its normal conical shape.

I am aware that it has been proposed to construct machines for pinning out hat-bodies while unfolded by pressing the hat-bodies between rotating cones or rollers; but such a construction does not give a uniform pressing action, and the tip or apex of the hat-body has been either left untouched or has been operated upon by additional small rollers, which would form lines or marks on the hat-body. By the use of the conical male and female dies of the proper size to receive the hat-body between them without creases I am able to impart a uniform pressure to the body practically all over its surface.

25. By screwing up or unscrewing the nuts *n* on the tie-rods *D*, above the cross-head *b*, the base-plate *D'* may be adjusted to bring the dies into proper relation with each other.

I claim as my invention—

30. 1. A machine for finishing felt hat-bodies to prepare them for shaping, said machine comprising a pair of heated conical male and female dies separable from each other and of a size and shape to receive and press the hat-bodies as they come from the battery, all substantially as described.

2. A machine for finishing felt hat-bodies to prepare them for shaping, comprising a pair of steam-heated conical male and female dies separable from each other and of a size 40 and shape to receive and press the hat-bodies as they come from the battery, all substantially as described.

3. The combination of a frame and a pair of conical dies adapted to receive and press a 45 hat-body as it comes from the battery, with means for imparting a short reciprocating motion to one of the dies, all substantially as described.

4. The combination of a frame and a pair 50 of conical dies adapted to receive and press a hat-body, with means for imparting a reciprocating motion to one of the dies, and devices for moving the other die toward and from the reciprocating die for the introduction and removal of the hat-body.

5. The combination of the frame and pair of conical dies adapted to receive and press a hat-body, with toggle-levers to raise and depress the lower die and a lever or treadle to 60 operate the toggles, all substantially as described.

In testimony whereof I have signed my name to this specification in the presence of two subscribing witnesses.

CHARLES E. KEATOR.
